COMBINED SIGN AND SUPPORT TOWER

Andrew W. Trucksess, Palmyra, N.J., assignor to Federated Department Stores, Inc., Cincinnati, Ohio, a corporation of Delaware

Filed Aug. 13, 1968, Ser. No. 13,123

Term of patent 14 years

Int. Cl. D20—03

U.S. Cl. D96—12

FIG. 1 is a side elevational view of a combined sign and support tower embodying my new design;

FIG. 2 is another side elevational view taken from a position 60 degrees from that of FIG. 1;

FIG. 3 is a top plan view thereof, the canopy being omitted for convenience of illustration; and

FIG. 4 is an enlarged cross sectional view taken on line 4—4 of FIG. 1.

I claim:

The ornamental design for a combined sign and support tower, substantially as shown.
